REMOTE CONTROL APPARATUS

Original Filed Feb. 19, 1929

INVENTOR:
P. P. Stoker,
by A. Z. Vencill,
His Attorney.

UNITED STATES PATENT OFFICE

PAUL P. STOKER, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

REMOTE-CONTROL APPARATUS

Application filed February 19, 1929, Serial No. 341,067. Renewed April 16, 1930.

My invention relates to remote control apparatus, and is particularly suitable for, though not limited to, the coded current control of railway traffic governing devices, such as signals, from a distant point.

One feature of my invention is the provision of means for avoiding the transmission of coded current for the control of a stop indication of a signal when a track relay which enters into the control of the signal has been deenergized.

I will describe one form of apparatus embodying my invention, and will then point out the novel features thereof in claims.

15 The accompanying drawing is a diagrammatic view, showing one form of apparatus embodying my invention.

Referring to the drawing, the reference characters 1 and 1^a designate the track rails 20 of a stretch Y of railway track connected with a siding Z by means of a switch F. The switch F may be controlled by any suitable means forming no part of my present invention, and omitted from the drawing for the sake 25 of simplicity. Switch F, when in its normal position as shown, directs traffic over stretch Y only, and when reversed, directs traffic over stretch Y to or from siding Z. A circuit controller operated by switch F comprises 30 contacts 42 and 72, which, while switch F is in its normal position connect with terminals 42^a and 72^a, respectively, and when switch F is reversed, connect with terminals 42^b and 72^b, respectively.

35 A section A—B of stretch Y is insulated from the adjoining portions of stretch Y and of siding Z by means of joints 2. Section A—B is provided with a track circuit which is supplied with current by a battery 3 connected across the rails adjacent one end of the section, and which includes a relay G connected across the rails adjacent the opposite end of the section. Relay G controls a slow releasing relay D.

45 Signal arms, designated by the reference characters S¹, S², S³ and S⁴, and which, as here shown, are of the semaphore type, govern the movement of traffic into section A—B. Arms S¹ and S², mounted on a common mast 50 adjacent location A, govern eastbound moves,

that is, moves toward the right as shown in the drawing, over switch F normal or reversed, respectively. Arms S³ and S⁴, adjacent location B, govern westbound moves over switch F normal or reversed, respectively. 55

Signal arms S¹ and S² are controlled by a relay H¹, and arms S³ and S⁴ are controlled by a relay H², the selection between the arms controlled by each of these relays being effected by the position of the switch-operated contacts 42 and 72, respectively. Relays H¹ and H² are provided with pick-up circuits which are controlled by selectors designated by the reference characters J¹ and J², respectively. Stick circuits for relays H¹ and H² are controlled by relay G. A third selector J³ at times causes the de-energization of 60 relays H¹ and H² by forming a shunt path around the windings of these relays. A resistance unit 32 prevents short-circuiting of 65 battery Q² when selector J³ forms a shunt path around the windings of relays H¹ and H². 70

Each of the selectors J¹, J² and J³ is provided with a contact 9 which is closed when 75 and only when its selector is energized by coded current to which the selector is responsive. Operation of selectors J¹, J², and J³ is effected by coded currents supplied over conductors 21 and 22 as controlled by a lever 80 V which may be placed with other similar levers in a suitable location such, for example, as a train dispatcher's office.

Lever V has a normal position N and two reverse positions L and R which are in opposite directions from position N. Two contact devices, M¹ and M², are operated by lever V. Each of these contact devices comprises a tube 10, constructed of an electrically insulating material and containing a quantity of an electrically conducting substance 11, which may, for example, be a liquid such as mercury. 90

With lever V in its normal position N, as shown, the tubes 10 are tilted in one direction so that the liquid conductor 11 occupies one end only of each tube. When either of the tubes is tilted into such a position that the end occupied by the liquid is higher than the opposite end, the liquid 100

passes to the opposite end through a small orifice 8, such a transfer of the liquid from one end to the other of either tube consuming an appreciable period of time. Terminals 59, 60, 62, 75 and 76 are set in the wall of the tube of device M^1 , and with lever V in its N position, as shown, are insulated from each other since tube 10 is electrical insulator.

Terminals 13, 14, 17, 45 and 46, which are set in the wall of tube 10 of device M^2 , are likewise insulated from each other when lever V is in its N position.

Upon the operation of lever V to position L, the end of tube 10 of device M^1 occupied by the liquid is raised above the opposite end of the tube, and hence liquid 11 is so shifted that it serves as a conducting medium between terminal 59 and terminals 60 and 62 until the liquid passes through orifice 8. Upon the subsequent return of lever V to position N, liquid 11 similarly serves, for a brief period of time, as a conducting medium between terminals 75 and 76. During the operation of lever V from position N to position L and its subsequent return to position N, the end of tube 10 of device M^2 occupied by liquid 11 continues in positions lower than the opposite end, and hence no connection is made from one terminal to another of device M^2 .

When lever V is operated to position R, however, the end of tube 10 of device M^2 occupied by the liquid is raised above the opposite end of the tube, and hence electrical connection is made through liquid 11 from terminal 13 to terminals 14 and 17. When lever V is returned from position R to position N, liquid 11 in device M^2 forms a conducting medium between terminals 45 and 46. Meanwhile in device M^1 , no connection is made between terminals when lever V is operated from its N to its R position and subsequently returned from its R to its N position.

Lever V, through contacts 13 and 14 of device M^2 , when operated to position R, causes a code transmitter C^1 to supply coded current for operating selector J^1 . When operated to position L, lever V, through contacts 59 and 60 of device M^1 , causes code transmitter C^1 to supply coded current for operating selector J^2 . Lever V, upon being returned from either position L or R to position N, causes code transmitter C^1 to supply coded current for operating selector J^3 when contact 49 of a polarized relay K is closed.

Relay K is of a type in which the polar contacts, after being closed in a given position by energization of the relay in a given direction, continue closed, after de-energization of the relay, until the relay is energized in the opposite direction. When lever V is operated to either the L or the R position, relay K becomes energized in the nor-

mal direction, causing its contact 49 to be closed. Current for energizing relay K in the reverse direction, causing contact 49 to open, is controlled by a selector J^4 which is operated by coded current supplied by a second code transmitter C^2 . Code transmitter C^2 supplies such coded current upon the de-energization of relay G when a train enters section A-B. Selector J^4 is provided with a contact 9 which is closed when, and only when, selector J^4 is energized by coded current from transmitter C^2 .

A source of current, here shown as a battery and designated by the reference character Q^1 , is provided adjacent the location of lever V. A second source of current, also shown as a battery, is designated by the reference character Q^2 , and is located adjacent switch F.

Having thus described, in general, the location and arrangement of the various parts comprising my invention, I will now describe the operation of the apparatus.

As shown in the drawing, all parts are in their normal condition, that is, lever V is in position N, contact 49 of relay K is open, each of the signal arms S is indicating "stop", switch F is in its normal position, section A-B is unoccupied, and contact 9 of each selector J is open. Section A-B being unoccupied, relay G is energized, and hence relay D is energized by its circuit passing from battery Q^2 , through wires 4 and 5, contact 6 of relay G, winding of relay D, and wire 7 back to battery Q^2 .

I will now assume that with these parts thus in their normal condition, the dispatcher, desiring to clear signal arm S¹ for a move over switch F normal, operates lever V to position R. The normal circuit for relay K is thus closed, passing from battery Q^1 , through wire 12, terminal 13 of device M^2 , liquid 11, terminal 17, wires 18 and 19, the normal winding of relay K, and wire 20 back to battery Q^1 . Relay K thereupon closes its contact 49.

When lever V is operated to its R position, a circuit for code transmitter C^1 is closed, passing from battery Q^1 , through wire 12, terminal 13 of device M^2 , liquid 11, terminal 14, wire 15, code transmitter C^1 , and wire 16 back to battery Q^1 . Code transmitter C^1 now supplies wires 21 and 22 with coded current which causes selector J^1 to close its contact 9, completing the pick-up circuit for relay H^1 , passing from battery Q^2 , through wires 4 and 5, contact 23 of relay G, wires 24 and 25, contact 9 of selector J^1 , wire 26, winding of relay H^1 , and wires 27, 28, 29, 30 and 31 back to battery Q^2 . Relay H^1 , upon becoming energized, completes, through its contact 37, its stick circuit passing from battery Q^2 , through wires 4 and 5, contact 23 of relay G, wire 24, resistance unit 32, wires 33 and 34, contact 35 of relay H^2 , wire 36, contact 37, 130.

of relay H^1 , winding of relay H^1 , and wires 27, 28, 29, 30 and 31 back to battery Q^2 .

As soon as liquid 11 of contact device M^2 has passed through orifice 8, the circuit for code transmitter C^1 is opened between contacts 13 and 14 of device M^2 , and hence transmitter C^1 ceases to supply coded current for the operation of selector J^1 . Selector J^1 then opens its contact 9 in the pick-up circuit for relay H^1 which, however, continues energized by its stick circuit just traced. Relay H^1 , upon becoming energized, completes, at its contact 40, the operating circuit for arm S^1 passing from battery Q^2 , through wires 4 and 5, contact 38 of relay G, wire 39, contact 40 of relay H^1 , wire 41, contact 42 of switch F, terminal 42^b, the operating mechanism for arm S^1 , and wires 44, 27, 28, 29, 30 and 31 back to battery Q^2 . Arm S^1 then moves to its "proceed" position.

If the despatcher should desire to return arm S^1 to its "stop" position before the arrival of a train, he will return lever V to its N position. Device M^2 thereupon completes a circuit for code transmitter C^1 passing from battery Q^1 , through wire 12, terminal 45, liquid 11, terminal 46, wires 47 and 48, contact 49 of relay K, wire 50, code transmitter C^1 , and wire 16 back to battery Q^1 . Transmitter C^1 now supplies wires 21 and 22 with a coded current which operates selector J^3 . Selector J^3 then closes its contact 9, completing a shunt path around the winding of relay H^1 in the stick circuit for relay H^1 , this shunt path passing from wire 33, through wire 51, and contact 9 of selector J^3 to wire 31. Relay H^1 , upon becoming shunted, opens its contact 37, breaking its stick circuit and opening its contact 40 in the circuit for arm S^1 which thereupon returns to its stop position.

If the despatcher should desire to send a train from location A to siding Z when switch F has been reversed, the operation is the same as that just described for sending a train over switch F normal except that, upon the energization of relay H^1 , arm S^2 is operated to its proceed position by a circuit which includes the circuit already traced for arm S^1 as far as contact 42, thence through terminal 42^b, wire 43, and the operating mechanism of arm S^2 to wire 44.

I will now assume that, with all parts again in their normal condition, the despatcher again clears arm S^1 for a move over switch F normal, and that a train passes location A, de-energizing relay G. Relay G, upon becoming de-energized, completes the operating circuit for code transmitter C^2 passing from battery Q^2 , through wire 4, contact 52 of relay G, wire 53, contact 54 of relay D, wire 55, transmitter C^2 , and wires 30 and 31 back to battery Q^2 . Transmitter C^2 then supplies wires 21 and 22 with the coded current which operates selector J^4 , causing selector

J^4 to close its contact 9 and complete the reverse energizing circuit for relay K passing from battery Q^1 , through wire 56, contact 9 of selector J^4 , wire 57, the reverse winding of relay K, and wire 20 back to battery Q^1 .

Upon the lapse of a brief period of time, relay D, its energizing circuit having been opened by relay G at contact 6, opens its contact 54, thus breaking the circuit for transmitter C^2 which then ceases to supply current to wires 21 and 22. Selector J^4 , being then de-energized, opens its contact 9 in the circuit for relay K, but in the meantime contact 49 of relay K has been operated to its reverse position and is thus open and continues open as long as relay K remains de-energized. Relay G, upon becoming de-energized also opens, at its contact 23, the stick circuit for relay H^1 . Relay H^1 , then becoming de-energized, opens, at its contact 40, the circuit for arm S^1 , causing arm S^1 to return to its stop position.

If, now, the despatcher returns lever V to its N position, the circuit for code transmitter C^1 , which causes transmitter C^1 to supply current for operating selector J^3 , is open at contact 49 of relay K, and hence transmitter C^1 does not supply such coded current to wires 21 and 22. The normal winding of relay K will again become energized upon the operation of lever V to either its L or its R position.

Assuming that the next operation of lever V is to its L position, the normal winding of relay K then becomes energized by a second circuit, which passes from battery Q^1 , through wire 58, terminal 59 of contact device M^1 , liquid 11, terminal 62, wires 63 and 19, normal winding of relay K, and wire 20 to battery Q^1 . Upon the operation of lever V to its L position, a circuit for code transmitter C^1 becomes closed passing from battery Q^1 , through wire 58, terminal 59 of contact device M^1 , liquid 11, terminal 60, wire 61, transmitter C^1 , and wire 16 to battery Q^1 . Transmitter C^1 , when energized by this circuit, supplies wires 21 and 22 with coded current which operates selector J^2 . Selector J^2 thereupon closes its contact 9, completing the pick-up circuit for relay H^2 passing from battery Q^2 , through wires 4 and 5, contact 23 of relay G, wires 24 and 25, contact 9 of selector J^2 , wire 64, winding of relay H^2 , and wires 28, 29, 30 and 31 back to battery Q^2 . Relay H^2 , then becoming energized, completes, at its contact 68, its stick circuit which follows the path previously traced for the stick circuit for relay H^1 as far as resistance unit 32, thence through wire 65, contact 66 of relay H^1 , wire 67, and contact 68 to the winding of relay H^2 .

Relay H^2 , upon becoming energized, also closes its contact 70, completing an operating circuit for arm S^3 or S^4 according to the position of switch F. If switch F is normal, 130

- the operating circuit for arm S^3 is completed, passing from battery Q^2 , through wires 4 and 5, contact 38 of relay G , wires 39 and 69, contact 70 of relay H^2 , wire 71, contact 72, terminal 72^a, the operating mechanism of arm S^3 , and wires 74, 29, 30 and 31 back to battery Q^2 . If, on the other hand, switch F were reversed, the operating circuit for arm S^4 would be completed, following the path just traced for the operating circuit for arm S^3 as far as contact 72, thence to terminal 72^b, wire 73, and the operating mechanism of arm S^4 to wire 74. If a train should enter section A—B when any one of the signal arms S^2 , S^3 and S^4 is indicating "proceed", the operation of the apparatus would be similar to that already described when a train enters section A—B while arm S^1 is indicating proceed.
20. From the foregoing description and the accompanying drawing, it is clear that my present invention, while providing means for supplying current of a given code for causing a signal to indicate stop, also provides that such coded current shall be supplied only when a track relay which enters into the control of that signal has continued energized while the signal was displaying a proceed indication. This avoids the unnecessary transmission of coded current for controlling the stop indication when the signal is already indicating stop, and thereby reduces the number of busy periods of the line, and makes the line available a greater portion of the time for the sending of coded currents for other purposes.
- Although I have herein shown and described only one form of remote-control apparatus embodying my invention, it is understood that various changes and modifications may be made therein within the scope of the appended claims without departing from the spirit and scope of my invention.
- Having thus described my invention, what I claim is:
1. In combination, a section of railway track, a track circuit for said section including a track relay, a signal for governing the movement of traffic into said section, a first selector responsive to current of a given code, a second selector responsive to current of a second given code, a manually operable device having a first and a second position, means controlled by said device in said second position for supplying current of said first code to said first selector, means controlled by said device in said first position for supplying current of said second code to said second selector if said track relay has continued energized following an operation of said first selector and until the return of said device to said first position, means for causing said signal to indicate "proceed" when said first selector is operated, and means for caus-

ing said signal to indicate "stop" when said second selector is operated.

2. In combination, a section of railway track, a track circuit for said section including a track relay, a signal for governing the movement of traffic into said section, a first selector responsive to current of a given code, a second selector responsive to current of a second given code, a manually operable lever having a normal and a reverse position, a polarized relay having a contact which is closed while said polarized relay is energized in a given direction and which continues closed until said polarized relay is energized in the opposite direction, means controlled by said lever for energizing said polarized relay in said given direction, means controlled by said track relay for energizing said polarized relay in said opposite direction, means controlled by said lever in said reverse position for supplying current of said first code to said first selector, means controlled by said lever in said normal position for supplying current of said second code to said second selector when said polarized relay contact is closed, means controlled by said first selector for causing said signal to indicate "proceed", and means controlled by said second selector for causing said signal to indicate "stop".

3. In combination, a section of railway track, a traffic governing device associated with said section and controlled in a given manner by current of a given code and controlled in a second manner by current of a second code, a manually operable lever having a normal and a reverse position, means controlled by said lever in said reverse position for supplying current of said first code for controlling said device, and means controlled by said lever in said normal position and also controlled by traffic conditions in said section for supplying current of said second code for controlling said device.

4. In combination, a section of railway track, a traffic governing device associated with said section and controlled in a given manner by current of a given code and controlled in a second manner by current of a second code, a manually operable lever having a normal and a reverse position, means controlled by said lever in said reverse position for supplying current of said first code for controlling said device, a relay controlled by said lever and by traffic conditions in said section, and means controlled by said lever in said normal position and by said relay for supplying current of said second code for controlling said device.

5. In combination, a section of railway track, a traffic governing device associated with said section and controlled in a given manner by current of a given code and controlled in a second manner by current of a second code, a manually operable lever having a

normal and reverse position, means controlled by said lever in said reverse position for supplying current of said first code for controlling said device, a polarized relay operated by current supplied in a normal direction by means controlled by said lever and operated by current supplied in the opposite direction by means controlled by traffic conditions in said section, and means controlled by said lever in said normal position and by a contact of said polarized relay closed in the normal direction for supplying current of said second code for controlling said device.

6. In combination, a section of railway track, a plurality of traffic governing devices associated with said section, means for selectively controlling said devices in a given manner by currents of various codes, means for collectively controlling said devices in a second manner by current of a given code, a manually operable lever having a normal position and a plurality of reverse positions, means controlled by said lever in said reverse positions for supplying currents of said various codes for controlling said devices in said first manner, and means controlled by said lever in said normal position and also controlled by traffic conditions in said section for supplying current of said given code for controlling said devices in said second manner.

7. In combination, a section of railway track, a plurality of signals associated with said section, a plurality of relays for selectively controlling said signals, a plurality of selectors each of which is responsive to current of a respective code, a given selector responsive to current of a given code, means for energizing each of said relays by one of said plurality of selectors respectively, means for de-energizing each of said relays by said given selector, a manually operable lever having a normal position and a plurality of reverse positions, means controlled by said lever in said reverse positions for supplying currents of said respective codes for controlling said plurality of selectors, and means controlled by said lever in said normal position and also controlled by traffic conditions in said section for supplying current of said given code for controlling said given selector.

8. In combination, a section of railway track, a track circuit for said section including a track relay, a signal associated with said section, a signal relay controlling said signal, a first selector, a second selector, a manually operable lever having a normal and a reverse position, means controlled by said lever in said reverse position for energizing said first selector, means controlled by said lever in said normal position and also controlled by said track relay for energizing said second selector, a pick-up circuit for said signal relay controlled by said first selector, a stick circuit for said signal relay controlled

by said track relay, and a shunt path around the winding of said signal relay controlled by said second selector.

9. In combination, a section of railway track, a track circuit for said section including a track relay, a signal associated with said section, a first, a second, and a third selector, means controlled by said first selector for causing said signal to indicate "proceed", means controlled by said second selector for causing said signal to indicate "stop", a manually operable lever having a normal and a reverse position, a polarized relay controlled in its normal direction by said lever and in its reverse direction by said third selector and having a contact which becomes closed when said polarized relay is energized in its normal direction and which continues closed until said polarized relay is energized in its reverse direction, means controlled by said lever in its reverse position for energizing said first selector, means controlled by said lever in its normal position and by said polarized relay contact for energizing said second selector, and means controlled by said track relay for energizing said third selector.

10. In combination with a device capable of responding in a given manner to a suitable form of energy and in a second given manner to the discontinuance of said energy, means including electric current of a given code for controlling the application of said energy to said device, means including electric current of a second given code for interrupting the supply of said energy to said device, a suitably controlled third means for at times also interrupting the supply of said energy to said device, a manually operable lever having a normal and a reverse position, a polarized relay controlled in its normal direction by said lever and in its reverse direction by said third means when said third means interrupts the supply of said energy to said device, means including said lever in its reverse position for controlling current of said first code which controls the application of energy to said device, and means including said lever in its normal position and also including a normally closed contact of said polarized relay for controlling current of said second code for discontinuing the supply of energy to said device.

11. In combination with a movable lever, a device, a code transmitter for delivering one code when said lever is moved to one position and another code when said lever is moved to a different position, means responsive to said one code for imposing one condition upon said device, means responsive to said different code for imposing another condition upon said device, and means effective when said device is in said one condition for preventing operation of said code transmitter even though said lever is moved to said one position.

12. In combination with a movable lever, a device, a code transmitter for delivering one code when said lever is moved to one position and another code when said lever is moved to a different position, means responsive to said one code for imposing one condition upon said device, means responsive to said different code for imposing another condition upon said device, independent means for imposing said one condition upon said device, and means effective when said device is in said one condition for preventing operation of said code transmitter in response to movement of said lever to said one position.
13. In combination with a movable lever, a device, a code transmitter for delivering one code when said lever is moved to one position and another code when said lever is moved to a different position, means responsive to said one code for imposing one condition upon said device, means responsive to said different code for imposing another condition upon said device, and means responsive to the actual condition of said device for at times preventing the operation of said code transmitter in response to movement of said lever to said one position.
14. In combination with a movable lever, a device, a code transmitter for delivering one code when said lever is moved to one position and another code when said lever is moved to a different position, means responsive to said one code for imposing one condition upon said device, means responsive to said different code for imposing another condition upon said device, and means responsive to traffic conditions adjacent said device for at times preventing operation of said code transmitter in response to movement of said lever to said one position.
15. In combination, a manually controlled element, means responsive to a certain operation of said element to transmit a code, a device, means responsive to such code for imposing a certain condition upon said device, and means responsive to the condition of said device for at times preventing the delivery of such code in response to such certain operation of said element.
16. In combination with a movable lever, a device, a code transmitter for delivering one code when said lever is moved to one position and another code when said lever is moved to a different position, means responsive to said one code for imposing one condition upon said device, means responsive to said different code for imposing another condition upon said device, and means responsive to the actual condition of said device for at times preventing the operation of said code transmitter in response to movement of said lever to said one position while permitting operation of said code transmitter in response to movement of said lever to said different position.

17. In combination with a movable lever, a traffic governing device, a code transmitter for delivering one code when said lever is moved to one position and another code when said lever is moved to a different position, means responsive to said one code for imposing one condition upon said device, means responsive to said different code for imposing another condition upon said device, and means responsive to traffic conditions adjacent said device for at times modifying the control of said code transmitter by said lever.

18. In combination with a movable lever, a traffic governing device, a code transmitter for delivering one code when said lever is moved to one position and another code when said lever is moved to a different position, means responsive to said one code for imposing one condition upon said device, means responsive to said different code for imposing another condition upon said device, mechanism responsive to traffic conditions adjacent said device, and means controlled by said mechanism for at times modifying the control of said code transmitter by said lever.

19. In combination with a movable lever, a traffic governing device, a code transmitter for delivering a first code when said lever is moved to one position and a second code when the lever is moved to a different position, means responsive to said first code for imposing one condition upon said device, means responsive to said second code for imposing another condition upon said device, means responsive to traffic conditions adjacent said device for at times delivering an indication code, and means responsive to said indication code for modifying the control of said code transmitter by said lever.

20. In combination with a movable lever, a traffic governing device, a code transmitter for delivering a first code when said lever is moved to one position and a second code when the lever is moved to a different position, means responsive to said first code for imposing one condition upon said device, means responsive to said second code for imposing another condition upon said device, means responsive to traffic conditions adjacent said device for at times delivering an indication code, and means responsive to said indication code for at times preventing operation of said code transmitter upon a movement of said lever to said one position while permitting operation of such code transmitter upon a movement of said lever to said different position.

21. In combination with a movable lever, a traffic governing device, a code transmitter for delivering a first code when said lever is moved to one position and a second code when the lever is moved to a different position, means responsive to said first code for imposing one condition upon said device, means responsive to said second code for im-

posing another condition upon said device, mechanism responsive to traffic conditions adjacent said device, and means controlled by said mechanism for at times preventing 5 operation of said code transmitter upon a movement of said lever to said one position while permitting operation of such code transmitter upon a movement of said lever to said different position.

10 22. In combination, a movable lever, a device located at a point remote from said lever, a code transmitter for delivering a code in response to a certain operation of said lever, means for conditioning said device in response to said code, and means responsive to 15 the condition of said device for at times modifying the control of said code transmitter by said lever.

23. In combination, a movable lever, a 20 movable device, a selector, a relay responsive to conditions adjacent said device, means controlled by said selector and said relay for operating said device, and a code transmitter controlled by said relay and by said lever 25 for operating said selector.

24. In combination with a line circuit, a 30 movable lever, a code transmitter controlled by said lever for delivering a code to said line circuit, a selector responsive to the code thus supplied to the line circuit, a relay responsive to conditions adjacent said selector, a device controlled jointly by said selector and said relay, an indicator adjacent said lever, and means controlled by said relay for 35 operating said indicator over said line circuit.

25. In combination with a railway signal, a 40 relay responsive to conditions adjacent said signal, a movable lever, a code transmitter controlled by said lever and by said relay, and means controlled by said code transmitter for operating said signal.

26. In combination with a movable lever, a 45 railway signal, a code transmitter for delivering one code when the lever is moved to a first position and another code when the lever is moved to a second position, means responsive to said one code to cause the signal to give one indication, means responsive to said 50 other code to permit the signal to give a different indication, and means responsive to traffic conditions adjacent said signal for at times preventing operation of said code transmitter upon a movement of said lever to 55 one of said positions while permitting operation of the code transmitter upon a movement of the lever to the other said position.

27. In combination with a line circuit, a 60 lever, a selector responsive to an indication supplied to said line circuit, a first code transmitter controlled jointly by said lever and said selector for delivering control codes to said line circuit, a section of railway track, a track relay for said section, a signal for 65 said section, means responsive to said con-

trol codes in said line circuit and controlled by said track relay for governing said signal, and means controlled by said track relay for at times supplying an indication code to said line circuit.

In testimony whereof I affix my signature.

PAUL P. STOKER.
